(57) **CLAIM**

The ornamental design of a housing of a handheld, portable, electronic device for music and other media content, as shown and described.

DESCRIPTION

FIG. 1 is a front, right and bottom perspective view of a housing of a handheld, portable, electronic device for music and other media content showing our new design;

FIG. 2 is a rear, right and top perspective view thereof;

FIG. 3 is a front, left and bottom perspective view thereof;

FIG. 4 is a front elevation view thereof;

FIG. 5 is a left side elevation view thereof;

FIG. 6 is a top plan view thereof;

FIG. 7 is a bottom plan view thereof;

FIG. 8 is a rear elevation view thereof; and,

FIG. 9 is a right side elevation view thereof.

The broken lines, which define the bounds of the claimed design, form no part thereof.

The broken lines environment are for illustrative purpose only and form no part of the claimed design.

1 Claim, 4 Drawing Sheets
